(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof where the right side view is a mirror image;

FIG. 5 is a top plan view thereof where the bottom plan view is a mirror image;

FIG. 6 is a perspective view thereof showing the state that when folding the subject design in half, the back cover part is pushed aside and then the transparent part on the front left side can be seen at the back side;

FIG. 7 is a perspective view thereof in which the subject design is folded in half;

FIG. 8 is a front view of FIG. 7;

FIG. 9 is a rear view of FIG. 7;

FIG. 10 is a left side view of FIG. 7;

FIG. 11 is a right side view of FIG. 7;

FIG. 12 is a top plan view of FIG. 7 where the bottom plan view is a mirror image; and,

FIG. 13 is a front view of FIG. 7 showing an example of the usage of the subject design.

The portions of the mobile phone shown in broken lines form no part of the claimed design. The broken lines in FIG. 13 that occur within the boundaries of the claim show an example of the mobile phone in a state of operation and form no part of the claimed design.
